Primary Examiner — Manpreet Matharu*Assistant Examiner* — Aula Soroush(74) Attorney, Agent, or Firm — Banner & Witcoff, Ltd.(57) CLAIM

The ornamental design for a shirt, as shown and described.

DESCRIPTION

FIG. 1 is a front left perspective view of a first embodiment of a shirt showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof; and

FIG. 7 is a top view thereof;

FIG. 8 is a front left perspective view of a second embodiment of a shirt showing our new design;

FIG. 9 is a rear perspective view thereof;

FIG. 10 is a front view thereof;

FIG. 11 is a rear view thereof;

FIG. 12 is a left side view thereof;

FIG. 13 is a right side view thereof; and,

FIG. 14 is a top plan view thereof.

The contrast in shading represents a contrast in appearance only and does not represent any particular color, material, texture or finish. The dot-dash lines adjacent to the shaded areas illustrate a boundary of the claim and form no part of the claimed design.

1 Claim, 14 Drawing Sheets(56)
